UNITED STATES PATENT OFFICE

THOMAS E. BRYAN, OF FORT WORTH, TEXAS

FLUID WELL CONSTRUCTION

Application filed June 1, 1931. Serial No. 541,445.

This invention relates to an improved fluid well construction and has more specific reference to an improved automatic fluid controlled valve arrangement for use in all kinds 5 of fluid wells including gas, oil and water.

It is common practice in well constructions to provide surface or external means for injecting fluid under pressure into the well tubing to start the flow of fluid from said well, 10 and to thereafter serve, at desired intervals, to stimulate continuous flow of the well fluid when the same fails to develop sufficient natural inertia or force to flow of its own accord.

In the particular embodiment herein illustrated the improvement resides in one or 15 more automatically operable check valves wherein each valve is closed so long as the fluid emanating from the well develops sufficient force to flow under its own power, 20 said valve serving also to permit outside pressure to enter the well automatically when the well fluid fails to flow under its own natural pressure.

The alleged novelty is predicated upon the 25 specific automatic check valve utilized in this arrangement, as well as the combination of said valve with the well tubing and casing.

The particular details of the valve as well 30 as its association with the tubing and casing will become more readily apparent from the following description and drawings.

In the drawings:

Figure 1 is a vertical sectional view 35 through a well developed in accordance with the present inventive conception showing two of the automatic fluid control valves in place.

Figure 2 is a fragmentary elevational view 40 showing one of said fluid control valves.

Figure 3 is a longitudinal sectional view 45 through the valve.

Figure 4 is a bottom plan view of said valve.

Figure 5 is a section on the line 5—5 of 50 Figure 1.

Figure 6 is a horizontal section through 55 the valve taken on the line 6—6 of Figure 3.

Referring first to Figure 1, the numeral 7 60 designates the well tubing. This is frequently referred to as the string of tubing and is

the means for conducting the well fluid (gas, water or oil), from the bottom of the well to the surface for usage.

The casing is denoted generally by the numeral 8 and surrounds the tubing in concentric spaced relation. In practice, I utilize a suitable gas or fluid pressure compressor or pump (not shown) for injecting fluid under pressure between the tubing and casing, and this is allowed to enter the tubing by way of the special automatic fluid control valve 9. This valve is of the construction seen in Figure 3 and is of appropriate proportions and includes an upper body section 10 threaded to a companion lower body section 11.

The bore of these two sections is fashioned to provide upper and lower valve seats 12 and 13 respectively. The valve unit is of duplex design and includes a cylindrical guide stem 14 provided with valve elements 15 and 16 engaging the respective seats 12 and 13.

Threaded on the outer ends of the valve body are duplicate caps 18 and 19 having gas or fluid discharge orifices or ports 20. The 75 upper end of the stem 14 extends through the top cap 18 and the lower end through the lower cap 19, said lower end being threaded to accommodate a pressure actuated disc 21. This disc is operated by the pressure of the 80 fluid (generally oil) in the well. These caps are provided with integral lugs 22 mounted in openings in the well tubing as seen in Figure 1. Incidentally, any number of these automatic control valves may be used in a 85 string of tubing.

The upper section 10 is provided with a screw-threaded hole 23 carrying a threaded pipe connection 24 also threaded into the pressure inlet opening in the tubing 7 as seen 90 in Figure 5.

Under normal conditions, when the fluid in the well is not flowing, the valves 15 and 16 drop down and become disengaged from the valve seats and to permit fluid pressure (gas) 95 from the compressor to pass through the valve and to be discharged through the ports 20 in the cap into the well tubing.

This gas under pressure obviously flows down between the tubing 7 and casing 8 and 100

enters the valve 9 by way of the pipe connection 24. Obviously then, when the valves are unseated, the gas flows out through the ports 20 and into the tubing and builds up sufficient pressure to stimulate a flow of the well fluid. When the flow in the tubing becomes sufficiently strong it acts against the valve closing disc 20 lifting the stem 14 and engaging the valves 15 and 16 with their respective seats. This checks further introduction of the external gas.

Under this arrangement it is possible to start the well to flow and whenever the well fluid recedes to an abnormal low pressure, 15 the valve 19 automatically opens to inject gas under pressure to reinstate the flow of well fluid.

The gist of the idea is in the provision of one or more valves located in the well tubing and having communication with the gas space between the tubing and casing, the valves being so constructed as to operate automatically to introduce gas under pressure when conditions require, to check said gas 25 when the well is flowing under its own pressure.

It is thought that the description taken in connection with the drawings will enable a clear understanding of the invention to be 30 had. Therefore, a more lengthy description is thought unnecessary.

While the preferred embodiment of the invention has been shown and described, it is to be understood that minor changes coming within the field of invention claimed may 35 be resorted to if desired.

I claim:

1. As a new product of manufacture, an automatic fluid control valve for well constructions comprising a tubular body having at least one internal valve seat and a screw-threaded opening adapted to accommodate a gas inlet pipe, apertured closing caps secured to opposite ends of said body, the apertures constituting gas outlets, means carried by said caps for attaching the valve to the interior of a string of well tubing, a valve stem slidable through guide openings in said caps and provided intermediate its ends with a valve element co-operable with the valve seat, said stem being provided on its lower end and outwardly of the adjacent cap with a fluid actuated disc for the purpose specified.

2. As a new product of manufacture, an automatic fluid control valve of the class described comprising a tubular body including upper and lower separable sections provided with upper and lower valve seats, upper and lower caps attached to the sections and provided with gas discharge ports, a valve stem slidable through the bore of the body, with its end portions slidable through guide openings in said caps, upper and lower valve units carried by the intermediate 65 portion of the stem and engageable with the

adjacent valve seats, the upper section of said body being provided with a screw-threaded hole to accommodate a gas inlet pipe, the lower end of said valve stem being provided with a fluid actuated disc arranged externally 70 of the adjacent end cap.

In testimony whereof I affix my signature.
THOMAS E. BRYAN.
